US00D741812S

(12) **United States Design Patent**
Leung

(10) **Patent No.:** **US D741,812 S**
(45) **Date of Patent:** **** Oct. 27, 2015**

(54) **ELECTRICAL JUNCTION BOX LID**

- (71) Applicant: **IPEX TECHNOLOGIES INC.,**
Mississauga (CA)
- (72) Inventor: **Kwan Yu Leung**, Mississauga (CA)
- (73) Assignee: **IPEX TECHNOLOGIES INC.,**
Mississauga (CA)

(**) Term: **14 Years**

(21) Appl. No.: **29/474,295**

(22) Filed: **Aug. 6, 2014**

(30) **Foreign Application Priority Data**

- Jul. 25, 2014 (CA) 157862
- (51) **LOC (10) Cl.** **13-03**
- (52) **U.S. Cl.**
USPC **D13/152**
- (58) **Field of Classification Search**
USPC D13/152, 184, 147, 156, 177, 119;
174/58, 53; D8/350; 220/328, 325;
403/408.1
- CPC F16B 5/02; F16J 13/06
- See application file for complete search history.

Assistant Examiner — Rhea Shields

(57) **CLAIM**

The ornamental design for an electrical junction box lid, as shown and described.

DESCRIPTION

FIG. 1 is a perspective view taken from the top and one side of the design;

FIG. 2 is a front elevational view of the design shown in FIG. 1;

FIG. 3 is a right side elevational view of the design shown in FIG. 1;

FIG. 4 is a rear elevational view of the design shown in FIG. 1;

FIG. 5 is a left side elevational view of the design shown in FIG. 1;

FIG. 6 is a top elevational view of the design shown in FIG. 1;

FIG. 7 is a bottom elevational view of the design shown in FIG. 1; and,

FIG. 8 is a bottom perspective view of the design shown in FIG. 1.

The broken lines are for the purpose of illustrating environment only and form no part of the claimed design.

1 Claim, 8 Drawing Sheets
